[57] CLAIM

The ornamental design for a lipstick case with triangular design, as shown and described.

DESCRIPTION

FIG. 1 is a perspective view of a lipstick case with triangular design showing my new design;

FIG. 2 is a rear elevation thereof;

FIG. 3 is a right side elevation thereof;

FIG. 4 is a left side elevation thereof;

FIG. 5 is a top plan view thereof;

FIG. 6 is a bottom plan view thereof;

FIG. 7 is a cross-sectional view taken along line 7—7 of
FIG. 1; and

FIG. 8 is an enlarged fragmentary view thereof.

FIG. 1

FIG. 2

FIG. 3

FIG. 4

FIG. 5

FIG. 6
